UNITED STATES PATENT OFFICE.

WILLIAM A. UTTZ, OF FORT WORTH, TEXAS.

KEY FASTENER.

Application filed January 24, 1921, Serial No. 439,397. Renewed May 2, 1922. Serial No. 557,981.

To all whom it may concern:

Be it known that I, WILLIAM A. UTTZ, a citizen of the United States of America, residing at Fort Worth, in the county of 5 Tarrant and State of Texas, have invented certain new and useful Improvements in Key Fasteners, of which the following is a specification.

My invention relates to locking keys and 10 particularly to safety attachments for door keys; and the object is to provide a simple device which can be attached to keys on the inside of a room or chamber to prevent burglars or other parties from opening the 15 doors. The advantage of such safety device is that it can be nested into compact form and may be carried in the pocket or attached to a key ring and so carried as readily as a key. Other objects and ad- 20 vantages will be fully explained in the following description and the invention will be more particularly pointed out in the claims.

Reference is had to the accompanying 25 drawings which form a part of this application.

Fig. 1 is a side elevation of the safety device and a key for the attachment mounted thereon. Fig. 2 is a side elevation, showing the same applied to a door key and a 30 part of the device broken away to show the construction and arrangement of the locking devices carried by the safety device. Fig. 3 is a view showing the sides or side coverings of the safety device, just as the same are struck from a piece of sheet metal. Fig. 4 is a plan view of the safety device. Fig. 5 is an enlarged side elevation of the 35 key for the safety device. Fig. 6 is a side elevation of a safety device which is a slight variation from the device previously shown. Fig. 7 is an enlarged view, showing a key for the form of safety device shown in Fig. 6 and showing a device 40 which may be used as a corkscrew.

Similar characters of reference are used to indicate the same parts throughout the several views.

The improved safety device has a longitudinal body member 1 and side members or covers 2 which cover parts of the sides of the longitudinal member 1 and form a housing for the locking devices. A cavity 3 is formed longitudinally in the member 1 and 50 latch 4 is mounted in said slot and a spring 5 is mounted in the slot and bears against

the end wall of the slot and against the latch 4. A key 6 is provided for holding and attaching the safety device to a door key 7. A vertical opening 8 is made in the member 1 and this opening intercepts the opening 2 in member 1. The latch 4 is beveled on the end and the key 6 is beveled at 8 and has a stop notch or catch shoulder 9 into which the latch 4 will be projected by the spring 5. 65 The latch 4 will yield for the catch 9 to pass down. The side member 2 has a slot 10 and a curved lug 11 is formed integral with the latch 4 and projects through the slot 10. The latch 4 can be released from the key 6 70 by pressing the lug 11 and the latch back against the tension of spring 5. The key 6 has a second catch 12 so that the key 6 may occupy the position shown in Fig. 1 or the position 75 shown in Figs. 2 and 4. The body 1 has the inner end reduced, leaving a shoulder 13 on the upper edge so that a key 7 may lie thereon with nothing to interfere with the rib 14 of the key, most keys having such rib. 80 The end 15 is formed into a bit for a screw driver. The end of the safety lock has nothing to do with the door lock and projects merely through the escutcheon of the door. The safety lock will prevent the 85 turning of the door key. The members 2 are formed with lugs 16 to be brazed to the member 1. A guard 17 is formed on the side member 2 so that a person cannot project an instrument past the key and safety de- 90 vice to manipulate the lug 11. The safety device will be adaptable for use with keys of different lengths and does not engage the door lock. The safety device has a hole 20 so that it can be carried on a key ring. 95 While being carried on a key ring, the key 6 will be carried as shown in Fig. 1, the handle being in line with the body 1.

The form of the safety device shown in Fig. 6 has an extension 19. This extension 100 provides for a key 6 with a longer shank which is formed into a corkscrew and the extension 19 forms a lifter for lifting the key 6 when it is being used as a corkscrew. The member 19 also makes a very efficient 105 bottle opener for opening capped bottles. A measuring scale will be made on one side of the device and a portion of one side made rough for striking matches.

What I claim, is,—

1. A key fastener comprising a body member to be projected into a door adja-

- 2
- 1 jacent to the door key, a spring-actuated latching member in said body, and a key to be projected through the eye of the door key into said body member to be engaged by 5 said latching member.
2. A key fastener for a door provided with lock and key comprising a body member to be projected into the door with the door key, a yielding latching member mounted 10 in said body member, and a key projected through the eye of the door key and into said body member to be engaged by said latching member.
3. A key fastener for a door provided with lock and key comprising a body member 15 having a longitudinal slot and a vertical slot intercepting the longitudinal slot, a yielding latching member mounted in said longitudinal slot, and a key projected 20 through the door key eye into said vertical slot past said latching member and engaged by said latching member.
4. A key fastener for a door provided
- with a lock and key comprising a body member having a longitudinal slot and 25 transverse slots, a yielding latching member mounted in said longitudinal slot and provided with an actuating lug integral therewith and projecting out of the said body, and a key projected through said 30 door key and into one of said transverse slots and engaged by said latching member.
5. A key fastener for a door provided with lock and key comprising a body member having a longitudinal slot and trans- 35 verse slots and forming a screw driver and a key lift, a yielding latching member mounted in said longitudinal slot, and a key to be projected through said door key and into one of said transverse slots to be engaged by said latching member and constituting a corkscrew.

In testimony whereof, I set my hand, this 18th day of January, 1921.

WILLIAM A. UTTZ.
